US00D960013S

(12) **United States Design Patent** (10) **Patent No.:** **US D960,013 S**
(45) **Date of Patent:** **** Aug. 9, 2022**

(54) **ASSET ACTIVITY TRACKER**

(71) Applicant: **Rooster, LLC**, Overland Park, KS (US)

(72) Inventors: **Ryan R. Konen**, Shawnee, KS (US);
Aaron L. Dale, Prairie Village, KS (US);
John W. Scott, Oathe, KS (US);
Steve R. Hardwick, Overland Park, KS (US);
Dustin M. Gary, Topeka, KS (US);
Doran N. Schwartz, Kansas City, MO (US);
Jarrod B. Piper, Topeka, KS (US)

(73) Assignee: **Rooster, LLC**, Overland Park, KS (US)

(**) Term: **15 Years**

(21) Appl. No.: **29/772,856**

(22) Filed: **Mar. 4, 2021**

(51) LOC (13) Cl. **10-05**

(52) U.S. Cl.

USPC **D10/106.1**

(58) **Field of Classification Search**

USPC D10/70, 104.1, 106.1, 128, 106.6;
D14/344, 242, 358, 230, 216, 496, 253,
D14/137; D16/237, 203

CLAIM

The ornamental design for an asset activity tracker, as shown and described.

DESCRIPTION

FIG. 1 is a top perspective view of an asset activity tracker showing our new design.

FIG. 2 is a bottom perspective view thereof.

FIG. 3 is a side view thereof.

FIG. 4 is a top view thereof; and,

FIG. 5 is a bottom view thereof.

1 Claim, 5 Drawing Sheets
